UNITED STATES PATENT OFFICE

171,930

VASE OR SIMILAR ARTICLE

Elinor Darby, Bethesda, Md.

Application July 15, 1953, Serial No. 25,954

Term of patent 7 years

(Cl. D29—28)

To all whom it may concern:

Be it known that I, Elinor Darby, have invented a new, original, and ornamental Design for a Vase or Similar Article, of which the following is a specification, reference being had to the accompanying drawing, forming a part hereof.

Figure 1 is a front perspective view of a vase or similar article showing my new design;

I claim:

The ornamental design for a vase or similar article, as shown.
